UNITED STATES PATENT OFFICE.

CHARLES GERALD WILFORD, OF LOS ANGELES, CALIFORNIA.

DESIGN FOR A JAR OR SIMILAR CONTAINER.

Application filed June 11, 1927. Serial No. 22,408. Term of patent 7 years.

To all whom it may concern:

Be it known that I, CHARLES GERALD WILFORD, a citizen of the United States, and a resident of Los Angeles, county of Los Angeles, and State of California, have invented a certain new, original, and ornamental Design for a Jar or Similar Container, and I do hereby declare that the following is a full, clear, and exact specification thereof, reference being had to the accompanying drawings, forming a part hereof.

I claim:

The ornamental design for a jar or similar container as shown.

In witness whereof, I have hereunto affixed my signature.

CHARLES GERALD WILFORD.
